UNITED STATES PATENT OFFICE.

FRANK E. BUCK, OF BALTIMORE, MARYLAND.

BUCKLE-RETAINER.

1,323,008.

Specification of Letters Patent. Patented Nov. 25, 1919.

Application filed April 22, 1919. Serial No. 291,814.

To all whom it may concern:

Be it known that I, FRANK E. BUCK, a citizen of the United States, residing at Baltimore, in the State of Maryland, have invented a new and useful Buckle-Retainer, of which the following is a specification.

It is the object of this invention to provide a simple means whereby a buckle or other ornament may be mounted on a pump or slipper and be held thereon by the pressure of the foot of the wearer, the construction being such that one buckle may be substituted for another, a flexible tongue serving as the means for retaining the buckle.

Another object of the invention is to provide a structure of the kind mentioned wherein the tongue will protect the pump from cutting the instep of the wearer.

A further object of the invention is so to construct the tongue that a pad may be mounted therein, to the end that the tongue may be adapted to the instep.

Within the scope of what is claimed, a mechanic may make changes, without departing from the spirit of the invention.

In the drawings:—

Figure 1 shows in side elevation, a pump whereunto the device forming the subject matter of this application has been applied, parts being broken away, and parts appearing in section;

Fig. 2 is a front elevation of the retainer, detached from the pump;

Fig. 3 is a rear elevation of the retainer;

Fig. 4 is a section on the line 4—4 of Fig. 2;

Fig. 5 is a section on the line 5—5 of Fig. 2;

Fig. 6 is a perspective showing one wall of the tongue before the same is completed;

Fig. 7 is a perspective disclosing the part of the tongue shown in Fig. 6, after the same has been completed.

In carrying out the invention, there is provided a buckle 1 which may be of any desired form. By way of illustration, merely, the buckle 1 is shown as provided with an opening 2, across which extends a bar 3 retaining a backing piece 4 made of leather or the like. The invention contemplates the use of a tongue 5, which may be fashioned from leather or any suitable material, the tongue including an inner wall 6 and an outer wall 7, these walls being stitched together with certain of their edges,

as shown at 17. The walls 6 and 7 are not united at one end by the stitching 17, and thus there is provided an opening 8 leading to a pocket which exists between the walls. A pad 9 may be inserted into the pocket, 60 through the opening 8. The pad 9 may consist of cotton or any other suitable material. The outer wall 7 is slit transversely, as shown at 25, the wall being stitched and drawn together, as indicated at 10, along 65 the edges of the slit to define angularly disposed parts in the tongue, the angle between said parts being indicated at 26. A stiffener 11, made of buckram or the like is interposed between the walls 6 and 7 of the 70 tongue 5. By means of staple fasteners 12, or in any other desired way, the tongue 5 is permanently secured to the buckle 1, and to the bar 3 if the buckle happens to be provided with such a bar. It is to be noted that 75 the fasteners 12 pass through the stiffener 11 and constitute the sole means for holding the stiffener in place. The stiffener 11, therefore, may be used or omitted without ripping the stitching 17 which holds the 80 walls 6 and 7 together, the stiffener being inserted at the time that the tongue is attached to the buckle by the fasteners 12.

In practical operation, the lower end of the tongue 5 is inserted beneath the upper 85 14 of a pump 15, and the foot of the wearer is thrust into the pump. Since the outer wall 7 of the tongue is slit at 25 and stitched at 10, the upper and lower ends of the tongue stand at an angle to each other, and 90 the buckle 1 will be inclined forwardly, away from the foot of the wearer so as to present an ornamental appearance. The buckle 1 may be removed at any time, simply by withdrawing the lower end of the 95 tongue 5 from beneath the upper 14. Thus, one buckle may be substituted for another upon short notice by the wearer. If the wearer desires to use a pair of spats, the buckle and the tongue may be removed by 100 a mere pull. The tongue serves to protect the pump from cutting the instep. A pad of one size may be substituted for another 105 pad at any time, or the pad may be removed entirely, the function of the pad being to shape the tongue 5 to the foot of the wearer.

I claim:—

1. In a device of the class described, a buckle; a flexible tongue comprising walls; 110

means for connecting both walls of the tongue with the buckle; and a stiffener between the walls and held therebetween solely by said means.

5. 2. In a device of the class described, a buckle; a flexible tongue provided with a pad-pocket having an opening; a pad in the pocket and insertible thereinto through the opening; and means for connecting the tongue to the buckle.
- 10 3. In a device of the class described; a buckle; a flexible tongue provided with a pad-pocket having an opening; a pad in the pocket and insertible thereinto through the opening; means for connecting the

tongue to the buckle; and a stiffener in the tongue and retained therein by said means.

4. In a device of the class described, a flexible tongue having a transverse slit, the tongue being drawn together along the 20 edges of the slit to fashion angularly disposed parts in the tongue; and a buckle carried by one of said parts.

In testimony that I claim the foregoing as my own, I have hereto affixed my signature in the presence of two witnesses.

FRANK E. BUCK.
